(57) **CLAIM**

The ornamental design for a part of an aerosol container, as shown and described.

DESCRIPTION

FIG. 1 is a perspective view of our part of an aerosol container in the closed position;

FIG. 2 is a perspective view of our part of an aerosol container in the opened position;

FIG. 3 is a front elevational view of our part of an aerosol container in the closed position; and,

FIG. 4 is a rear elevational view of our part of an aerosol container in the opened position.

The broken line showing of a container in FIGS. 1-4 is included for the purpose of illustrating only and forms no part of the claimed design.
